UNITED STATES PATENT OFFICE.

CHARLES E. LUCKE, OF NEW YORK, N. Y., ASSIGNOR TO THE YALE & TOWNE MANUFACTURING COMPANY, OF STAMFORD, CONNECTICUT.

DOOR CHECK AND CLOSER.

Application filed May 6, 1922. Serial No. 559,012.

To all whom it may concern:

Be it known that I, CHARLES E. LUCKE, a citizen of the United States, and a resident of New York, in the county of New York and State of New York, have invented certain new and useful Improvements in Door Checks and Closers; and I do hereby declare the following to be a full, clear, and exact description of the invention, such as will enable others skilled in the art to which it appertains to make and use the same.

This invention relates to improvements in door checks and closers, and more particularly to such as employ checking means including a piston operable in a cylinder and connected through the medium of suitable instrumentalities with the door.

In the operation of devices of this type, during the closing of the door, the resistance of the checking medium,—fluid for example,—against the piston causes side thrust of the spindle against its bearing and this results in an undue amount of friction unless thoroughly lubricated, and it is desirable also that the pitman connection with the crank of the spindle shall also be thoroughly lubricated.

One object of my present invention is to provide simple and efficient means whereby ample and thorough lubrication shall be insured at the spindle bearing, and also at the bearing of the pitman in its connection with the crank of the spindle.

With this and other objects in view, the invention consists in certain novel features of construction and combinations of parts as hereinafter set forth and pointed out in the claims.

In the accompanying drawings; Figure 1 is a view partly in section showing the application of my improvements to a door check and closer; Figure 2 is a partial end view of the same, and Figures 3, 4, 5 and 6 are views showing modifications.

The checking cylinder of the device is indicated at 1, said cylinder being closed at its respective ends by means of heads 2 and 3 and intended to contain suitable checking fluid. The checking cylinder 1 is provided with an opening having a threaded wall for the accommodation of a threaded packing nut or bearing member 4, through which the spindle 5 of the device passes. The spindle 5 is provided with a crank 6 (located within the cylinder 1) and said crank has a

journal 7 mounted in a socket 8 in the lower portion of the cylinder. A checking piston 9 is located within the cylinder 1 at one side of the center of the latter and is connected, through the medium of a pitman 10 with the crank 6.

The packing nut or bearing member may be provided with an upward tubular extension 11 to contain packing means 12 for the spindle and this packing means may properly be retained in place by a nut 13 threaded into said tubular extension. The bearing member 4 is also made with an annular depending extension 14 in which the lower end portion of the spindle 5 has its bearing. In the lower portion of the bearing member 4, an annular groove 15 is formed to surround the lower portion of the spindle for the purpose of receiving lubricant (as hereinafter described) for the purpose of thoroughly lubricating the spindle bearing at this point to reduce to a minimum the friction which would otherwise occur by reason of the side thrust against the spindle during the operation of the checking means when the door is closing.

The bearing member 4 may be provided therein with an annular lubricant collecting chamber 16 (above the lubricant groove 15) to receive lubricant which might work upwardly from the lower spindle bearing, and the lubricant thus collected may find its way into the cylinder at the non-compression side of the piston, through a passage such as indicated at 17.

The cylinder 1 is provided on its head 2 with an enlargement 18 and on its top with an enlargement 19,—one of said enlargements being, in effect, a continuation of the other. Communicating ducts 20, 21 are formed (preferably by drilling) in the cylinder enlargements 18, 19 and the duct 20 is connected with the compression chamber of the cylinder 1 by a short duct 22 in the cylinder head 2. The duct 21 extends to the packing nut or bearing member 4 and communicates with a peripheral groove 23 in said nut or member. One or more ducts 24 in the packing nut or bearing member connect the peripheral groove 23 with the inner annular groove 15.

The by-pass formed by the ducts 20, 21, 22 and 24 and the groove 23, affords a passage for checking fluid from the compression chamber of the cylinder to the lubri-

cant groove 15 in the nut or bearing member 4, and this fluid, serving as a lubricant, will be caused to pass to the lubricant groove 15 under pressure when the piston 9

5 approaches the head 2 of the cylinder in the operation of the device during the closing of the door and the lower bearing of the spindle will be kept thoroughly lubricated.

10 A duct 25 in the cranked lower portion of the spindle communicates at one end with the annular lubricant groove 15 and at its other end with a duct 26 in the crank 6,—said duct 26 extending to the central portion of said crank with which the pitman 10 is 15 connected; and is provided with lateral branch ducts 27 which communicate with an annular groove 28 around the bearing for the pitman 10 in the connection of the latter with the crank 6.

20 It is apparent that when lubricant is forced to the annular groove 15 for lubricating the spindle bearing as previously described, lubricant will be caused to pass from said groove, through the ducts 25, 26 25 and 27 and annular groove 28 and afford thorough lubrication for the connection between the pitman 10 and the crank 6.

Instead of forming lubricant by-pass ducts 20, 21, 22, 23 and 24 in the manner 30 above described, I may employ a tube 29 connected at one end with the compression chamber of the cylinder and at the other end with the lubricant groove 15 in the packing nut or bearing member 4, as illustrated in Figures 3 and 4.

In the embodiment of the invention shown in Figure 5, the arrangement of 40 lubricant passages between the annular lubricant groove 15 and the bearing for the pitman connection with the crank 6, are the same as shown in Figure 1, but instead of conducting lubricating fluid from the end of the cylinder, through passages in parts of the cylinder walls and bearing member 4 as shown in Figure 1, provision is made 45 for causing lubricant to pass through the piston and pitman to the bearing for the pitman in its connection with the crank 6, and thence to the lubricant groove 15,—the travel of the lubricant in the arrangement shown in Figure 5 being reverse to the direction of flow of lubricant in the arrangement shown in Figure 1. In the construction 50 shown in Figure 5, the piston 9 is provided with a duct or passage 30 extending through it and communicating at one end with the compression chamber in the cylinder 1. The other end of this duct or passage 55 communicates with an annular groove 31 in the wrist pin 32 which connects the pitman with the piston, and the groove 31 is connected by passages, indicated at 33, with an annular groove 34 at the center of the wrist pin. The central annular groove 60 65 34 in the wrist pin communicates, through a

duct or passage 35 extending longitudinally through the pitman with the annular lubricant groove 28 in the pitman-bearing portion of the crank 6.

In the construction shown in Figure 6, 70 the pitman is sufficiently extended (as at 36) to meet the inner face of the piston, and a duct or passage 37 extends directly through the piston, wrist pin and pitman, the crank pin being provided with a central 75 annular groove 38 to afford proper connection of the portion of the duct or passage 37 in the crank pin with those portions which extend through the piston and pitman.

Various slight changes might be made in 80 the details of construction of my invention without departing from the spirit thereof or limiting its scope and hence I do not wish to restrict myself to the precise details herein set forth.

Having fully described my invention what I claim as new and desire to secure by Letters-Patent, is:—

1. The combination with the spindle of a 90 door closer, said spindle provided with a crank, a spindle bearing, a cylinder, a piston therein, and a pitman connecting said piston with the spindle crank, of a passage-way leading from the cylinder in front of the piston to the spindle bearing in proximity 95 to the spindle crank, whereby, upon the compression stroke of the piston, lubricant will be forced from the cylinder, through said passage-way to said spindle bearing.

2. The combination with the spindle of a 100 door closer, said spindle having a crank, a spindle bearing, a cylinder, a piston therein, and a pitman connected with said piston and having connection with the crank of the spindle, said crank having lubricant receiving 105 means, whereby the connection of the pitman with the crank may be lubricated, of a passage-way communicating with the spindle bearing near the spindle crank, also with the lubricant receiving means of the crank 110 and also with the cylinder in front of the piston, whereby, upon the compression stroke of the piston, lubricant will be forced from the cylinder through said passage-way to the spindle bearing and also to the lubricant receiving means of the crank. 115

3. The combination with the spindle of a 120 door closer, said spindle having a crank, a cylinder, a piston in the cylinder, a pitman connected with the piston, a bearing for said pitman in its connection with the crank of the spindle and a bearing for the spindle, of passages leading from the compression end of the cylinder to one of said bearings, and passages leading from said last mentioned bearing to the other bearing, whereby lubricant will be forced to said bearings during compression stroke of the piston. 125

4. The combination with the cylinder, piston, cranked spindle, and pitman of a door 130

check and closer, of a bearing for the spindle, a bearing in the connection of the pitman with the crank of the spindle, each of said bearings having an annular lubricant groove, means for conducting lubricant from the compression end of the cylinder to the annular groove of the spindle bearing, and means for conducting lubricant from said last-mentioned annular groove to the annular groove in the bearing for the pitman on the crank of the spindle.

5. The combination with the checking cylinder of a door check and closer, and a bearing member for the spindle of the closer, said bearing member having a lubricant groove of a passage-way communicating with the compression portion of the cylinder and with said lubricant groove for conveying checking fluid under pressure 20 from said checking cylinder to said lubricant groove.

6. The combination with the cylinder, piston and spindle of a door check and closer, of a bearing member for said spindle having lubricant receiving means, and a passageway for conveying checking fluid under pressure from the compression chamber of the cylinder to said lubricant receiving means in the spindle bearing member.

30 7. In a door check and closer, the combination of a cylinder, a piston therein, a spindle, operating connections between said pis-

ton and spindle, a bearing member for the spindle, said bearing member having a lubricant groove therein near its lower portion and also having a peripheral groove and a duct connecting said grooves, and said cylinder provided with ducts connecting the compression chamber formed therein with said peripheral groove in the bearing member, whereby approach of the piston toward the outer end of the compression chamber formed by the cylinder will cause checking fluid to be forced to said lubricant groove to lubricate the spindle bearing.

8. In a door check and closer, the combination with a cylinder, a piston therein, a spindle, and operating connections between the spindle and piston, of a bearing member for the spindle having an annular lubricant groove, means for conveying checking fluid under pressure from the cylinder to said lubricant groove, said bearing member having a lubricant collecting chamber above said annular lubricant groove and having a passage connecting said chamber with the cylinder.

In testimony whereof, I have signed this specification in the presence of two subscribing witnesses.

CHARLES E. LUCKE.
